UNITED STATES PATENT OFFICE.

WILLIAM J. DE WITT, OF AUBURN, NEW YORK, ASSIGNOR TO THE SHOE FORM CO. INC.,
OF AUBURN, NEW YORK, A CORPORATION OF NEW YORK.

EXPANSIBLE SHOE FORM.

Application filed August 23, 1927. Serial No. 214,897.

This invention relates to shoe forms characterized by being hollow in form and light in weight, and which are also capable of being contracted (as upon insertion into the shoe) 5 and then expanded.

The form includes generally a hollow toe member made of suitably resilient material, such as molded sheet celluloid, having inwardly directed marginal edges adjacent to 10 the sole, upon which may be mounted an expansion (and contraction) element. It may also include a reinforcing cross piece which is permanently attached to one of the edges and slidably engages the opposite edge.

15 A typical and preferred embodiment of the invention is shown by the accompanying illustrations, in which:

Fig. 1 is a bottom view of a shoe form made in accordance with the invention;

20 Fig. 2 is a longitudinal cross section of a shoe with the form fitted therein;

Fig. 3 is an enlarged cross section of the slideway and slide shown in Fig. 1;

25 Fig. 4 is a bottom view of a shoe form similar to that in Fig. 1, with the reinforcing cross piece removed;

Fig. 5 is an enlarged elevation of a modified form of slideway of celluloid with a slide member thereon;

30 Fig. 6 is an enlarged elevation of a further modified form of slideway of celluloid having a slide member thereon and a reinforcing wire therein;

Fig. 7 is a bottom view, with parts broken away, of a modification;

35 Fig. 8 is a side view of the slideway and slide of Fig. 7;

Fig. 9 is a bottom view of a further modification of the shoe form in which the slideway 40 comprises a slot;

Fig. 10 is a sectional view of the slide and slot shown in Fig. 9;

Fig. 11 is a cross section of one form of the cross piece shown in (Fig. 1); and

45 Fig. 12 is a cross section of a modified form of cross piece having a filler strip therein.

In the drawings, the toe member 1 fits within the toe of the shoe 2 and is forced into position therein by an expanding (and contracting) element 3, which comprises cross-wires 4, 5 which are attached to the toe member, and a compression member 7, which bears against the heel 6 of the shoe. The toe member 1 is hollow and may be conveniently fashioned from sheet celluloid or other shape re-

taining, resilient material and is provided with longitudinal marginal edges 8, 9 which are turned in along the sides of the toe member and are adapted to lie upon the insole of the shoe 2 when in position. Each of these 60 marginal edges is provided, in the rear portion with a slideway (11, 12) which may consist of an arched wire 13 riveted to the edge at its ends as at 14, 15 and forming a substantially horizontal slideway along its intermediate portion 16.

The cross-wires 4, 5 are pivoted at their forward ends 17, 18, respectively, to the forward portions of the marginal edges 8, 9, and at their rear ends carry slide members 19, 20 70 (shown as rings) which slidably engage the slideways 12, 11 respectively, as by looping about them (Fig. 3) intermediate their ends, as at 16. At the point of intersection of the cross-wires 4, 5, a slide member engages them, 75 such as the ring 22 on the end of the compression strip 7. The latter may be made of a stiffly resilient material such as steel wire and extends rearwardly to engage the heel 6 of the shoe 2.

80 Mounted transversely of the toe member is a cross piece 23 which may be laminated and fashioned from two strips of celluloid 24, 25, cemented together intermediate the ends, receiving one of the marginal edges 8 therebetween at one end (to which they are permanently affixed as by cement) and at the other end receiving the opposite margin 9 in the space 26 therebetween, with a freely slidable engagement (see Fig. 11). The strips 24, 25, 85 may also have a filler strip 27 inserted therebetween, intermediate of the ends, to which both of the strips 24, 25 are attached as by cement (see Fig. 12) thus spacing these strips apart by an amount equal to the thickness 90 of the marginal edges 8, 9.

95 In use, the shoe form (with the side walls of the toe member slightly contracted) is thrust into the toe of the shoe, and the compression strip 7 bent sufficiently to permit its 100 free end to be introduced into the shoe and then allowed to spring back against the heel 6 (Fig. 2). This thrust of the form into the shoe and the continued thrust of the compression member is transmitted to the cross-wires 105 4, 5, of which the forward ends are thrust directly forward, pushing the toe member firmly into the toe of the shoe, while the rear portion of each of the cross-wires 4, 5, tends to swing about these pivoted forward ends 110

as a fulcrum (urged by the thrust of the compression strip transmitted through the sliding ring 22) and to be thrust laterally outward, bearing all the while upon the slideways 11, 12 along which the ends of the cross-wires slide freely with each movement. This tends to expand the sides of the toe member and thus to fill out the shoe and make it smooth. But it is to be observed that this expanding effect is obtained after the toe member has been thrust firmly forward into the toe of the shoe and has thus filled out and developed the upper of the shoe to its full length,—a feature which is especially desirable in the display of 15 footwear generally.

For the withdrawal of the shoe form from the shoe, the compression member 7 is first bent sufficiently to permit the release of its rear end from the heel of the shoe. It is then 20 drawn straight back. The ring 22 is thus made to slide back on cross-wires 4, 5 drawing their rear ends together and thus contracting the toe member of the form and permitting it to be easily removed from the shoe.

25 The slideways 11, 12 may be attached to the marginal edges, as described, when made of metal, but they may also be fashioned from celluloid or the like. In this case, they may be attached to the marginal edges of the toe member by cementing or fusing the ends to the surface of the marginal edges as at 28, 29, (Fig. 5). This may also be done when the intermediate portion 16 is made of celluloid and contains a reinforcing metal wire 16' embedded therein as shown in Fig. 6. In these 30 forms, the slide members of the cross wires adapted to engage the slideways 11, 12, may consist of the end of the wire, passed below the slideway and bent upwardly at its free 35 end, as at 21—in Figs. 7 and 8 thus preventing retraction.

40 As a further modification of the forms thus described, the slideways 11, 12 may be replaced by longitudinal slots 11', 12' (Fig. 9) 45 in the marginal edges of the toe member and the slide members 19, 20, may be upwardly disposed projections or the bent up ends of the cross-wires 4, 5, slidably to engage said slots, as shown in Fig. 10.

50 It will be clear from the above disclosure that other modifications in the arrangement and construction of the several parts may be made, within the invention, but such modifications are to be understood as comprehended by 55 the above specification and included within the terms of the following claims.

I claim:

1. A shoe form, comprising a resilient, hollow, toe member having slideways, inturned 60 marginal strips along the sides of the toe member, expansion and contraction means 65 engaging the slideways, and a compression member adapted to bear against the heel of the shoe and to expand said means longitudinally and laterally of the shoe when un-

der compression and to contract upon being released.

2. A shoe form, comprising a hollow toe member, a pair of cross-wires positioned therein, one end of each of said cross-wires being pivoted to the toe member, a slide member on the free end of each of said cross-wires, slideways on the toe members to receive the slide members, and a compression member slidably engaging the cross-wires adjacent 75 to their intersection.

3. A shoe form, comprising a toe member, marginal strips thereon, a pair of cross-wires, the wires being pivotally attached at their forward ends to the forward portion of the 80 marginal strips, slide members on the rear ends of the wires, slideways on the rear portion of the marginal strips to receive the slide members, and a compression member 85 slidably engaging the cross-wires adjacent to their intersection.

4. A shoe form, comprising a toe member, inturned marginal strips along the sides thereof, longitudinal slideways in the rear portion of the inturned strips, a pair of 90 cross-wires pivoted at their forward ends to the forward portion of the marginal strips and engaging the longitudinal slideways at their rear ends, and a compression member engaging the cross-wires at their intersection. 95

5. A shoe form comprising a hollow resilient toe member of readily fusible sheet material, inturned strips along the opposite sides thereof, a pair of cross-wires having their forward ends pivoted to said strips, 100 slideways welded to said marginal strips, slide members on the rear ends of said cross-wires slidably engaging said slideways, and a compression member slidably receiving said cross-wires adjacent to their intersection and 105 extending rearwardly to bear against the heel of the shoe.

6. A shoe form comprising a resilient, hollow, toe member, inturned marginal strips along the opposite sides thereof, expansion 110 and contraction means connected to said strips, a compression member connected to said means, to expand and contract the same laterally of the shoe, and a transverse member affixed to one of the marginal strips and 115 slidably engaging the opposite strip.

7. A shoe form comprising a resilient, hollow, toe member, inturned marginal strips along the opposite sides thereof, expansion 120 and contraction means connected to said strips, a compression member connected to said means, to expand and contract said means laterally of the shoe, and a laminated transverse member affixed to one of the marginal strips and slidably engaging the opposite strip between said laminations. 125

8. A shoe form, comprising a resilient hollow, toe member, inturned marginal strips along the opposite sides thereof, a pair of cross-wires attached to the marginal edges 130

at one end and slidably engaging said edges at their opposite ends, a compression member attached to said cross-wires adjacent to their intersection, and a transverse member attached to one of said strips and slidably engaging the opposite strip.

9. A shoe form, comprising a hollow resilient toe member, inturned marginal strips on the opposite sides thereof, slideways on 10 said strips, a pair of cross-wires attached to the marginal strips at the forward ends and slidably engaging said strips at their opposite ends, a compression member attached to said cross-wires adjacent to their intersection, and a transverse piece affixed to one of the strips, the other end being split, slidably 15 to receive the other marginal strip therebetween.

10. A shoe form, comprising a hollow toe member, inturned marginal strips on the opposite sides thereof, expansion and contraction means engaging said marginal edges, and a transverse piece permanently attached to one of the marginal edges and frictionally engaging the opposite strip. 20 25

11. A shoe form, comprising a hollow toe member, inturned marginal strips on the opposite sides thereof, expansion and contraction means engaging said marginal edges, and a laminated cross piece permanently attached to one of the marginal edges and slidably 30 engaging the opposite edge between its laminations.

Signed by me at Boston, Mass., this 19th day of August, 1927.

WILLIAM J. DE WITT.
